CURTAIN SUPPORT

Filed May 4, 1931

FIG-1

FIG-2

William C. Campbell INVENTOR.

BY *Curtis V. Bush*
ATTORNEYS.

UNITED STATES PATENT OFFICE

WILLIAM C. CAMPBELL, OF DAVENPORT, IOWA

CURTAIN SUPPORT

Application filed May 4, 1931. Serial No. 534,755.

My invention relates to improvements in curtain supports.

The objects of my invention are:

1. To provide a curtain support readily applicable to window casings without defacement of the window casings and which should be readily adjustable vertically as well as being adapted to hold a pair of curtains or a curtain and lambrequin at different 10 distances in front of the window casing;

2. To provide means by which the curtain support will be concealed from view from the front by the curtains.

I attain these objects by the means illustrated in the accompanying drawing, in which.—

Figure 1 is a plan view of my device, but showing the curtain rods in dotted lines and broken away to shorten the figure;

20 Figure 2 is a side elevation of my device;
Figure 3 is a vertical elevation looking at

it from the direction of the window sash.

25. My appliance comprises a vertical hanger throughout the several views.

25 My appliance comprises a vertical hanger formed preferably from a single flat strip of metal having a body, 1, with a brace, 2, head, 3, and point, 4, formed integral therewith and bent as shown in the drawing. The brace, 2,
30 is bent laterally at right angles to the body, 1, and is preferably formed in triangular shape as shown in Figure 3. The head is formed by bending the upper end of the brace, 2, downwardly and at right angles to the brace.

35 and the extreme end of the head is cut to a triangular shape, 4, to form a point which is sharpened at $4a$ and may be driven into the top of the window casing.

Upon the body, 1, I mount a slidable bracket, 5, the intermediate portion of which is formed into a rectangular loop to fit snugly upon the body, 1. One end, 5b, of the bracket extends directly forward from the loop and the remaining portion of the bracket is bent at 5a so that the portion, 5c, stands at right angles to the end, 5b, and is rebent so that the end, 5b', stands outwardly parallel with the end, 5b.

53 Telescoping rods, 6 and 6a, of flat tubular section, are slidingly mounted upon the ends,

5b, of the brackets, and similar rods, 7 and 7a, are mounted upon the ends, 5b', of the brackets. The projecting ends, 5b and 5b', may be formed flat or round or in any other desired shape, but the flat tubular form shown is preferable on account of its superior ability to resist sagging at the middle. 55.

The brackets, 5, may be mounted upon the body, 1, as shown in Figure 1, with the ends, 5b', to the outside, but I prefer to make these brackets reversible, so by simply turning them upsidedown and changing sides, we think the ends, 5b', will stand between the ends, 5b.

When arranged as shown in Figure 1, the outer lambrequin or curtain will extend beyond the bodies, 1, and conceal them largely from view.

The brackets, 5, are slideable vertically up-
on the bodies, 1, and may be adjustable at any
desired height. The brackets are adjustable
by manually sliding the loop portion, 5, up-
wardly or downwardly upon the body, 1.
As the arms, 5b and 5b', extend forwardly
and carry the crossbars or rods, 6 and 7 and
6a and 7a, the weight of the crossbars is
utilized to lock the brackets in their adjusted
position, the loop portion, 5, of the brackets
being formed to fit closely upon the bodies, 1,
so that a very slight tilting of the brackets
will cause them to bind upon the bodies, 1,
and hold them in the desired adjustment.
This is of especial convenience in cases where
curtains are shortened by shrinking or other-
wise. 75 80 85 89

My curtain support is mounted upon the top of a window casing by placing the head over the top of the casing and then driving the point, 4, down into the window casing. The body, 1, then extends downwardly along the front of the casing and the brackets may be then adjusted to the desired height. As the ends, 5b and 5b', of the brackets extend forwardly, the weight of the curtains and of the curtain rods, will tend to tilt the brackets downwardly so as to make them bind upon the bodies, 1, and secure them firmly in the desired position.

It is obvious that the heads, 3, may be secured to the window casings by nails, screws ¹⁰⁰ screws.

or other equivalent means instead of by the points, 4, but the points, 4, are a little more convenient to apply and are very readily removed and do not mar the window casings where it can be noticeable.

5 If desired, my brackets may be applied to the lower sash of the window or to any other space desired to be curtained, as well as to the window casing, and the heads may be modified to meet the requirements of any particular case without departing from the spirit of my invention.

10 I claim:

15 1. A curtain support comprising a body having a head united thereto at right angles, a reversible bracket slidably mounted upon the body and having forwardly extending ends, and means for securing the head to a window casing.

20 2. A curtain support comprising a body having a head united thereto at a right angle, a vertically adjustable reversible bracket mounted upon the body and having forwardly extending spaced ends, and means for securing the head to a window casing.

25 In testimony whereof he affixes his signature.

WILLIAM C. CAMPBELL.
